US00D963908S

(12) **United States Design Patent** (10) **Patent No.:** **US D963,908 S**
Lalli et al. (45) **Date of Patent:** **** Sep. 13, 2022**

(54) **MEDICAL DEVICE LIGHTING MODULE**

(71) Applicant: **CEEK Women's Health, Inc.**,
 Portland, OR (US)

(72) Inventors: **Maria Lalli**, Portland, OR (US);
Wesley Hare, Portland, OR (US); **Katie Lee**, Portland, OR (US); **Christian Freissler**, Portland, OR (US); **Chase Thompson**, Portland, OR (US); **Jia Lu Ni**, Portland, OR (US)

(73) Assignee: **CEEK Women's Health, Inc.**,
 Portland, OR (US)

(**) Term: **15 Years**

(21) Appl. No.: **29/690,667**

(22) Filed: **May 9, 2019**

(57) **CLAIM**

The ornamental design for a medical device lighting module, as shown and described.

DESCRIPTION

FIG. 1 is a front, right side, and top perspective view a medical device lighting module of our design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The dash-dash broken lines form portions of the medical device lighting module that form no part of the claimed design.

1 Claim, 4 Drawing Sheets
